UNITED STATES PATENT OFFICE.

EDWIN HART, OF WATERBURY, CONNECTICUT, ASSIGNOR TO THE WATERBURY WATCH COMPANY, OF SAME PLACE.

DESIGN FOR A CYCLOMETER-CASING.

SPECIFICATION forming part of Design No. 25,773, dated July 14, 1896.

Application filed May 29, 1896. Serial No. 593,671. Term of patent 14 years.

To all whom it may concern:

Be it known that I, EDWIN HART, of Waterbury, in the county of New Haven and in the State of Connecticut, have invented and produced a new and original Design for a Cyclometer-Casing; and I do hereby declare that the following is a full, clear, and exact description thereof, reference being had to the accompanying drawings, in which—

10 Figure 1 is a perspective view of my cyclometer-casing, and Fig. 2 is an end view thereof.

Letters of like name and kind refer to like parts in each of the figures.

15 The object of my invention is to provide a new shape or design of a casing for cyclometers for use more especially on bicycles; and to this end said invention consists in the design for the casing of a cyclometer, substantially as hereinafter specified.

The leading feature of my design is the shape or form of the casing in cross-section, such being flat or a plane surface on one side, and arched or curved convexly on the opposite side. As shown in the drawings, the bot-

tom of the casing A is flat and the top arched or curved convexly, the curve being a semi-circle, whose ends merge into straight or plane surfaces that form the casing sides. The ends of the casing are flat. Thus the general shape of the casing is semicylindrical.

The sight-openings for enabling the index-wheels of the registering mechanism to be seen are provided in the curved top, and, of course, suitable means, not necessary to be shown, are provided for the attachment of the casing with its inclosed mechanism to a bicycle.

Having thus described my invention, what I claim is—

40 The design for a cyclometer-casing, substantially as set forth.

In testimony that I claim the foregoing I have hereunto set my hand this 21st day of May, A. D. 1896.

EDWIN HART.
